[57] CLAIM

The ornamental design for a toothbrush package/holder, as shown and described.

DESCRIPTION

FIG. 1 is a right side elevational view of a toothbrush package/holder showing our new design;
 FIG. 2 is a front elevational view thereof;
 FIG. 3 is a left side elevational view thereof;
 FIG. 4 is a rear elevational view thereof;
 FIG. 5 is an enlarged top plan view thereof;
 FIG. 6 is an enlarged bottom plan view thereof;
 FIG. 7 is a top, front, and right side perspective view thereof;
 FIG. 8 is a vertical cross-sectional view thereof, taken along line 8—8 of FIG. 7; and,
 FIG. 9 is a top, front, and right side perspective view thereof, shown in an open condition.
